BURNER STRUCTURE

Clarence A. Herman, Grosse Pointe Farms, Mich.,
assignor to Detroit-Michigan Stove Company,
Detroit, Mich., a corporation of Michigan

Application July 24, 1939, Serial No. 286,256

5 Claims. (Cl. 158—116)

This invention relates generally to gas burners and refers more particularly to those designed for use in gas ranges and the like. Heretofore it has been customary to provide the head of a 5 burner of this type with a number of outlet holes or ports for the gas. In many instances such ports are provided by drilling the head of the burner at predetermined points. This alone is a time-consuming and expensive step in the manufacture of such burners. However, if the ports 10 so made are not small enough to prevent the ignited gas from flashing or working back into the head and mixing chamber of the burner, there may be serious consequences, and if the over-all 15 number of such ports is not sufficient to provide the proper flame, the burner is inefficient. Ordinarily it is quite difficult and expensive to drill the required number of ports of the proper size, therefore I have designed a burner structure to 20 overcome such difficulties.

One of the essential objects of the present invention is to provide a burner wherein the gas ports are formed by superposed stampings and the like that can be accurately made and assembled to produce the desired results.

Another object is to provide a burner structure that is easier and less expensive to make than the drilled type of burner mentioned above.

Another object is to provide a burner wherein 30 the over-all number of ports may be increased or decreased according to the number of superposed parts employed.

Another object is to provide a burner wherein the gas entrance end of each port is smaller 35 than the exit end thereof so that the flow of gas through the port will be such as to cause the ignited gas to burn close to the exit end of each port instead of being blown away or outwardly therefrom.

40 Another object is to provide a burner wherein it is possible for more primary air to be used in the mixing tube of the burner so that less secondary air is required at the exit end of each gas port to provide the proper combustion.

45 Another object is to provide a burner structure that is easier to clean and service and wherein in replacement of parts may be readily and accurately accomplished whenever desired.

Another object is to provide a burner wherein 50 the top part of the superposed members mentioned may be of sufficient area to serve as a cooking plate.

Another object is to provide a burner with 55 such a cooking plate that effectively conceals and prevents the flame from being extinguished by

spilling foods, and prevents the latter from entering or clogging the gas ports of the burner.

Other objects, advantages and novel details of construction of this invention will be made more apparent as this description proceeds, especially 5 when considered in connection with the accompanying drawing, wherein:

Figure 1 is a side elevation, with parts broken away and in section, of a burner structure embodying my invention; 10

Figure 2 is a fragmentary top plan view of the burner with the superposed members removed from the head thereof:

Figure 3 is a detail plan view of the uppermost part of said superposed members; 15

Figure 4 is a detail plan view of one of the corrugated parts of said superposed members;

Figure 5 is a detail plan view of one of the intermediate parts of said superposed members;

Figure 6 is an enlarged fragmentary plan view 20 of one of the corrugated parts;

Figure 7 is a sectional view taken on the line 7—7 of Figure 6;

Figure 8 is a plan view of the assembled superposed members fanned out for cleaning purposes; 25

Figure 9 is a fragmentary vertical sectional view through a slight modification.

Referring now to the drawing, A is the mixing chamber, and B is the head of a gas burner embodying my invention. 30

As shown, the head B and mixing chamber A are integral and are preferably formed as a single casting. As usual, the mixing chamber A is tubular in form and is provided at its free end with an enlarged mouth portion 10 provided with a gas supply pipe 11 and a shutter 12 by means of which the amount of primary air passing into the chamber A may be readily controlled. 35

The head B is likewise tubular in form and extends substantially vertically from the mixing chamber A. The upper end of this head is open and carries a number of superposed stampings which provide the ports for gas. As shown, the stampings C and D, respectively, are identical in construction. Each comprises a ring 13 having 40 radially extending corrugations 14 and having a diametrically extending attaching bar 15. The stamping E intermediate the stampings C and D is a plain flat ring 16 having a diametrically extending attaching bar 17. The uppermost stamping F is a flat disk. In Figures 1 to 8, inclusive, the area of each stamping C, D, E and F is the same and is substantially equal to the outside area 45 of the open upper end of the head B. As shown, the stamping D is lowermost and has its corruga-

50
55

tions 14 resting on the upper end 18 of the head B. The stamping E rests upon the corrugations 14 of the stamping D. The corrugations 14 of the stamping C rest on the stamping E, and the flat disk F rests upon the corrugations 14 of the stamping C. Thus, four sets 19, 20, 21 and 22, respectively, of ports for gas are formed by the superposed parts illustrated, the lowermost set 19 being formed by the corrugations 14 of the stamping D and the upper end 18 of the head, the set 20 by the corrugations 14 of the stamping D and the stamping E, the set 21 by the stamping E and the corrugations 14 of the stamping C, and the set 22 by the corrugations 14 of the stamping C and the disk F.

By varying the number of stampings in the assembly, the over-all number of sets of ports may be varied accordingly. For example, if only two sets of ports are desired, the stampings C 20 and E would be dispensed with so that the disk F could rest upon the corrugations 14 of the stamping D. If six or more sets are desired, additional stampings such as C and E are interposed between the disk F and the upper stamping C.

In the present instance, each set of ports is substantially the same in contour and cross section and each port has an entrance end 30 which receives gas from the interior of the head B and 30 has an exit end 31 where gas is discharged to be ignited. Actually the entrance end 30 of each port is smaller than the exit end 31 thereof, and the side walls 32 and 33 of each of said ports are gradually flared from the entrance end 30 to 35 the exit end 31 so that the flow of gas through each port will be such as to cause the ignited gas to burn close to the exit end 31 of each port instead of being blown away or outwardly therefrom. The cross sectional area of each port is 40 such as to preclude the ignited gas flashing or working back into the head B, yet the over-all number of such ports is such that a proper flame is assured. Especially is this so when both the 45 number of sets of ports and the shutter 12 for primary air can be so easily controlled. In fact, my construction is such that more primary and less secondary air may be used to provide the proper combustion.

For anchoring the stampings in place relative 50 to the head, I have provided a crossbar 40 within and fixed to the head adjacent the upper end thereof and a screw 41 that engages aligned openings 42, 43, 44 and 45, respectively, in the stampings and threadedly engages the crossbar 40.

To permit the parts to be cleaned while maintaining their assembled relation, I have provided 55 a hollow rivet 46 that extends through aligned openings 47, 48, 49 and 50, respectively, in the stampings and swivelly connects the same together. Thus, when it is desired to clean the structure, the screw 41 is removed from the crossbar 40 and stampings C, D, E and F so that the latter as a sub-assembly may be bodily removed from the head E. The individual stampings may 60 then be swung around the hollow rivet 46 as illustrated in Figure 8 so that they will be accessible for cleaning purposes.

In Figure 9 I have illustrated a slight modification in which the top part F' of the superposed members is of sufficient area to serve as a cooking plate. As shown, this plate F' is thicker and larger in diameter than the disk F and extends over and beyond the burner opening 60 in the top frame 61 of the gas range. The plate F' may 65 be a casting and is anchored by a screw 41a to

the crossbar 40 of the burner. To permit the products of combustion to escape from under the plate F', there are a plurality of legs 63 on the underside of the plate F' and resting on the top frame 61 of the range. Thus, these legs 63 space the plate F' a sufficient distance above the top frame 61 to provide vents 64 for the products of combustion and transmit the load from the plate F' to the top frame 61 instead of to the burner head B.

What I claim as my invention is:

1. A burner having an upright tubular head open at its upper end, an assembly of superposed stampings on the open upper end of the head and providing radially extending passages for a combustible mixture, a permanent swivel connection between the stampings of the assembly maintaining their relative superposed relation but permitting relative lateral movement therebetween for cleaning purposes, and a separate detachable connection between said assembly and said head normally holding said stampings against the lateral movement aforesaid.

2. In a burner, an assembly of superposed plate-like members adapted to be mounted on a supporting head and providing radially extending passages for a combustible mixture, a permanent swivel connection between the plate-like members of the assembly maintaining their relative superposed relation but permitting relative lateral movement therebetween for cleaning purposes, and means for detachably connecting said assembly to the supporting head and normally holding said plate-like members against the lateral movement aforesaid.

3. A burner having an upright tubular head open at its upper end, an assembly of superposed stampings on the open upper end of the head and providing radially extending passages for a combustible mixture, removable means carried by 40 the head for holding the plate-like members in position relative to the head, and a connection between said plate-like members operable when the means aforesaid is removed to hold the plate-like members together while permitting relative 45 lateral adjustment thereof for cleaning purposes.

4. A burner having an upright tubular head open at its upper end, a radially corrugated ring resting upon the open upper end of said head and cooperating therewith to provide radially extending 50 passages for a combustible mixture, a flat ring resting on the corrugated ring and cooperating therewith to provide radial passages for a combustible mixture, a radially corrugated ring resting on the flat ring and cooperating therewith 55 to provide radially extending passages for a combustible mixture, and a flat top plate resting on the last mentioned corrugated ring and cooperating therewith to provide radial passages for a combustible mixture, removable means carried by 60 the head for holding the rings and top plate in position relative to the head, and a connection between said rings and top plate operable when the means aforesaid is removed to hold said parts together while permitting relative lateral 65 adjustment thereof for cleaning purposes.

5. A burner having an upright tubular head open at its upper end, a radially corrugated ring resting upon the open upper end of said head and cooperating therewith to provide radially extending 70 passages for a combustible mixture, a flat ring resting on the corrugated ring and cooperating therewith to provide radial passages for a combustible mixture, a radially corrugated ring resting on the flat ring and cooperating therewith to 75

provide radially extending passages for a combustible mixture, and a flat top plate resting on the last mentioned corrugated ring and cooperating therewith to provide radial passages for a combustible mixture, the rings having diametrically extending bars, the top plate and bars just mentioned having two sets of registering openings, a removable securing element carried by

the head engaging one set of openings and normally holding said rings and top plate in position relative to the head, and a rivet engaging the other set of openings and operable when the securing element is removed to hold the rings and top plate together while permitting relative lateral adjustment thereof for cleaning purposes.

CLARENCE A. HERMAN.
